VACUUM BREAKER

William E. Sloan and Irving H. Russell, Chicago,
Ill., assignors to Sloan Valve Company, Chicago,
Ill., a corporation of Illinois

Application September 14, 1934, Serial No. 743,976

10 Claims. (Cl. 137—69)

Our invention relates to an improvement in vacuum breakers and has for one purpose the provision of an improved vacuum breaker for employment with pipes delivering water or other liquids. A particularly apt use of our invention is for flush valves for toilets, urinals, or the like, but we wish it understood that our invention is not limited to this specific use. One object of our invention is to prevent back-syphonage of water from a toilet bowl or the like. Another object is the prevention of any freezing or sticking from lack of use or corrosion. Another object is the provision of means for permitting the use of a large air inlet with sufficient air to satisfy the vacuum. Another object is the provision of means for maintaining atmospheric pressure at the spud of the fixture in order to prevent water from rising in the flush pipe during a vacuum. Other objects will appear from time to time in the course of the specification and claims.

We illustrate our invention more or less diagrammatically in the accompanying drawing, wherein—

Figure 1 is a side elevation illustrating the location of our device in relation to the flush valve and closet bowl, urinal or the like.

Figure 2 is a vertical section on an enlarged scale; and

Figure 3 is a detail.

Like parts are indicated by like symbols throughout the specification and drawing.

Referring to the drawing, 1 generally indicates a closet bowl, urinal or the like. Inasmuch as the details do not of themselves form part of the present invention they are not shown. 2 indicates any suitable water supply pipe whereby water may be passed for the flushing of the toilet. 3 indicates any suitable flush valve structure the details of which are not herein shown; although this invention is adapted to be built into the flush valve as an integral part of it. It will be understood, however, that the handle 4 may be manually employed to actuate the flush valve 3 whereby a predetermined quantity of water is allowed to pass through the pipe 2 to the fixture 1 in order to flush it. 5 generally illustrates our vacuum breaker, it being shown as interposed between the flush valve 3 and the fixture 1, to which it may be connected, for example, by any suitable pipe or connection 6.

50 The member 5 may be threaded to the pipe 6 as at 7. It may be provided with any suitable threaded locking connection 8 whereby it may be secured to the lower portion of the flush valve 3. 9 is any suitable leakage preventing washer. 10 indicates 55 a member or seat screwthreaded into one portion

of the member 5 and provided with a lip 11 upon which the washer 9 is positioned. It will be understood that normally the water discharge through the flush valve 3 passes downwardly through the member 10 and out through the pipe 6 to the fixture.

The member 5 is shown as having a lateral enlargement generally indicated as 12 which is provided with an upper aperture screwthreaded as at 13 to receive a guide or spider including the outer annulus 14, the inner cylindrically apertured sleeve 15 and the connecting members 16. The sleeve portion 15 is extended upwardly as at 17 to receive a bell shaped protector or cover 18 which may be mounted in place as by any suitable pin or bolt 19. Its lower edge 20 extends downwardly about and below the upper edge 21 of the annulus 14, whereby there is room for a free circulation of air upwardly about the edge 20, over the edge 21, and downwardly through the space about the sleeve 15.

The annulus 14 is herein shown as terminating in a valve seat 22 having a relatively sharp inner edge 23 as the lowest portion thereof. Adapted to be positioned against this valve seat 23 is the rubber valve member 24 which may be formed with any suitable brass or metallic insert 25 mounted upon a stem 26. The upper portion of the stem 26, herein shown as hexagonal in cross section, penetrates the interior of the sleeve 15. The lower portion is reduced and is screwthreaded as at 27 to receive a weight 28. Washers 29, 30, may be employed to abut against the upper and lower edges of the rubber valve portion 24. If desired, instead of the screwthreading 27, or to supplement it, a set screw 31 may be employed to hold the weight 28 on the pin 26 and to lock the entire assembly together. It will be understood that the pin 26 is intended to slide freely within the sleeve 15. We find it advantageous to form the exterior of the pin in such fashion that it does not oppose extended abutting surfaces of metal to the metal of the sleeve 15. Employing a hexagonal cross section inserted within a cylindrical walled sleeve tends to prevent the probability of its becoming frozen in place by lack of use or corrosion.

While the upward movement of the valve 24 is limited by its engagement with the lip 23, its downward movement is limited by the below described lever 35. This lever structure includes a central hub or enlargement 36 which may rotate about the transverse pin 37. One end of the lever 35 is provided with a more or less rounded abutment portion 39 against which the weight 28 gravitally seats itself. The opposite arm 40 of

the lever terminates in a sleeve 41 having an aperture 42 through which passes a pin 43 headed as at 44. This pin is in more or less loose fit in relation to the aperture 42. It carries at its upper end a lever actuating disc 45 adapted to seat snugly against the opposed lower edge 46 of the member 11. The disc 45 has formed in its upper surface one or more relatively shallow depressions 47 the purpose of which will later appear.

10 In the use of our device, when the valve is not being employed, the weight 28 rests upon the rounded end 39 of the lever arm 35 and thereby forces the opposite arm 40 into the position in which it is shown in full line in Figure 2. This 15 snugly seats the actuating disk 45 against the opposed surface 46 of the member 11. Air can freely pass inwardly about the sleeve 15 and downwardly about the valve member 24 into the passage 6, whereby a large volume of air may be 20 admitted at the end of each flush. This air inlet, being covered by a bell or cover, is well protected and is not easily stopped up, even intentionally. The normal position of the device is that shown in full line in Figure 2, with the 25 weight 28 in its lower position, and a substantial clearance between the valve 24 and the opposed valve seat 23. The weight 28 is sufficient to hold the actuating disc 45 snugly in the position in which it is shown in Figure 2 against the opposed surface 46. In the event that a vacuum 30 occurs above said disc, atmospheric air can slowly pass into the space above the disc through the passages 41. Small apertures through the disc might be employed, but we find it preferable to form the shallow apertures 47 in the face of the disc, as they are less likely to be stopped up.

35 When a user actuates the flush valve, as by pressure upon the manual handle 4, a substantial amount of water is rather suddenly released through the flush valve 3 and flows through the member 10. The pressure or impact of this water against the actuating disc 45 is sufficient to lower the lever arm 40 and to raise the lever arm 39, with the result that the valve surface 24 is 40 snugly thrust against the opposed valve seat 23, cutting off any entry of air or escape of water about the bell or cover 18. This valve is closed as long as the flush water is passing downwardly 45 to the pipe 6. The air valve 24 closes instantly at the slightest flow of water through the flush outlet, through the action of the disc 45. It is kept tightly seated and leak-proof during the flush, not only by the flow of water on and about 50 the disc 45, but by the water pressure against the lower side of the air valve. When the flush water has ceased to flow the valve 24 is mechanically unseated by the following factors. In the first place, the weight of the parts, including the 55 weight 28, tends to clear the valve. In the second place, the partial vacuum occurring at the end of each flush, due to the water dropping down the flush connection, tends to draw the valve 24 downwardly. In the third place, there 60 is the tendency of the soft rubber seat 24 to resist compression and to throw itself off from the metal seat 23 above it.

65 The disc 45 in the flush outlet has two main functions. In the first place, it closes the air valve during the flush, in the manner above outlined. In the second place, through the apertures 47 it gradually admits air to the supply line if there is a vacuum in the supply pipe, while at the same time maintaining atmospheric pressure 70 below the disc. When such a vacuum occurs

it is desirable that it be slowly broken, so as to prevent a vacuum of any degree below the disc, and a drawing up of water thereby. The close fit between the disc 45 and the opposed surface 46 prevents this sudden back pressure or drawing up of water, but it gradually disperses the vacuum above the disc. The relatively shallow apertures or grooves have the advantage of being not readily stopped up or clogged. The loose fit of the pin 43 permits the disc 45 to seat itself 10 snugly against the opposed surface 46.

The above described vacuum breaker may be employed in a wide number of uses but operates particularly well on closet and urinal bowls where a periodic or occasional flushing is desired. It will operate properly on any closet bowl, regardless of back pressure, when properly installed above the spill line of the fixture, and will prevent back-syphonage with any degree of vacuum in the supply line. Its action is 20 independent of the flush valve and it will work with any flush valve or flush water supply or control means. It is simply and easily applied to any installation. It has no springs or ball mechanism to get out of order. Atmospheric 25 pressure is maintained at the spud of the sanitary fixture at all times, so that a vacuum never reaches the spud. Practice has proved that in spite of the large volume of air admitted at the 30 end of each flush, the operation is quiet and free from air noises. Nothing that will go through a flush valve can clog or damage our vacuum breaker, as the smallest opening in the breaker is much larger than the maximum opening 35 through any flush valve.

It will be realized that whereas we have described and shown a practical and operative device, nevertheless many changes may be made in the size, shape, number and disposition of parts without departing from the spirit of our invention. We therefore wish our drawing and description to be taken as in a broad sense illustrative and diagrammatic rather than as limiting us to our specific showing. It will be also understood that whereas our invention may be 40 particularly applied to flush valves we do not wish its use to be so limited.

We claim:

1. In a vacuum breaker, a water inlet connected with a source of water supply, an air inlet on the discharge side of the water inlet and communicating with the atmosphere, a chamber with which both the water inlet and the air inlet communicate, said chamber providing at all times a free open communication between the water inlet and the air inlet, said chamber having an outlet, a pivoted lever located in said chamber, one end of said lever projecting under the water inlet, a valve member connected with said end for controlling the passage of air through said water inlet in a reverse direction to that of the passage of the water therethrough, the other end of said lever projecting under said air inlet, a valve member at said latter end for controlling said air inlet so that when water flows through the water inlet it strikes the water inlet valve member, and through the agency of said lever moves the air inlet valve member to close said air inlet to prevent water from escaping therethrough, and when the water ceases to flow through said water inlet 70 said lever automatically moves to close said water inlet and open said air inlet, said water inlet valve member being provided with a leakage means through which air from the air inlet passes through said water inlet in a reverse direction to 75

that of the flow of water therethrough when the air inlet is open, whereby syphonage is prevented and any vacuum on the supply side of the water inlet is gradually broken.

5. 2. In a vacuum breaker, a water inlet connected with a source of water supply, an air inlet on the discharge side of the water inlet and communicating with the atmosphere, a chamber with which both the water inlet and the air inlet communicate, said chamber providing at all times a free open communication between the water inlet and the air inlet, said chamber having an outlet, a pivoted lever located in said chamber, one end of said lever projecting under the water inlet, 10 a valve member connected with said end for controlling the passage of air through said water inlet in a reverse direction to that of the passage of the water therethrough, the other end of said lever projecting under said air inlet, a valve member 15 at said latter end for controlling said air inlet so that when water flows through the water inlet it strikes the water inlet valve member, and through the agency of said lever moves the air inlet valve member to close said air inlet to prevent water from escaping therethrough, and when the water ceases to flow through said water inlet said lever automatically moves to close said water inlet and open said air inlet, said water inlet valve member being provided with a leaking means 20 through which air from the air inlet passes through said water inlet in a reverse direction to that of the flow of the water therethrough when the air inlet is open, whereby syphonage is prevented and any vacuum on the supply side of the water inlet is gradually broken, said air inlet valve member and water inlet valve member being adjustably supported on said lever.
3. In a vacuum breaker, a water inlet connected with a source of water supply, an air inlet on the discharge side of the water inlet and communicating with the atmosphere, a chamber with which both the water inlet and the air inlet communicate, said chamber providing at all times a free open communication between the water inlet and the air inlet, said chamber having an outlet, a pivoted lever located in said chamber, one end of said lever projecting under the water inlet, a valve member connected with said end for controlling the passage of air through said water inlet in a reverse direction to that of the passage of the water therethrough, the other end of said lever projecting under said air inlet, a valve member at said latter end for controlling said air inlet so that when water flows through 25 said water inlet it strikes the water inlet valve member, and through the agency of said lever moves the air inlet valve member to close said air inlet to prevent water from escaping therethrough, and when the water ceases to flow through said water inlet said lever automatically moves to close said water inlet and open said air inlet, said water inlet valve member being provided with a leaking means through which air from the air inlet passes through said water inlet in a reverse direction to that of the flow of the water therethrough when the air inlet is open, whereby syphonage is prevented and any vacuum on the supply side of the water inlet is gradually broken, the air inlet being provided with a projecting portion which projects into said chamber and is surrounded by an air space and which is engaged by the air inlet valve member.
4. A vacuum breaking device for use in connection with flush valves having water supply and discharge pipes, comprising means for introduc-
- ing air into the discharge pipe of said flush valve, said introducing means including an air opening into the discharge pipe approximately as large as the supply pipe, and a limiting admission means for admitting a limited amount of air from the discharge pipe into the supply pipe of said flush valve, so that a vacuum on the supply side of the water inlet is gradually broken, said limiting means including a check-valve which opens freely to permit discharge of water, but which closes to prevent passage back of more than the said limited amount of air when a vacuum in the supply pipe is being broken, whereby the contemporaneous formation of a vacuum condition in the discharge pipe is substantially prevented.
5. Means for passing water to a subjacent device from a water supply means and for preventing back flow of water from said device to said supply means when the pressure in the latter falls below the pressure of the atmosphere, comprising a casing formed with a water inlet in its top wall for water from said supply means, a lower water outlet to said device, and an air inlet opening in its top wall laterally displaced from said water inlet, a vertically disposed tubular member mounted in said opening and formed at its lower end with a valve seat and having a tubular valve guide axially disposed in its upper portion, a lever within said casing pivoted to turn about a horizontal axis intermediate said inlets, a valve member mounted on one end of said lever to turn into an upper position in which it extends across and closes said water inlet, but adapted to be turned into a lower position to open said water inlet by water flowing into said casing through said water inlet, said lever having at its other end an uprising portion with a convex upper surface and a weighted valve member having an uprising stem working in said guide, and having a smooth underside engaged and supported on said convex upper surface of said lever and moved by the latter into position to engage said seat and close the passage through said tubular member when the first mentioned valve member is moved into its open position, and adapted to move downward under gravitational action, when no water is passing through the latter into said casing through said water inlet, to thereby open said passage and turn the first mentioned valve member into position to close said water inlet.
6. A vacuum-break'ng device for a liquid-discharge line descending to a receptacle open to atmosphere, comprising a casing adapted for connection into said line and provided with a descending passageway constituting, when installed, a portion of said line; said passageway including a liquid inlet at the top, a liquid outlet at the bottom, and a central chamber connecting said inlet with said outlet, there being an air inlet into the central chamber located higher than the liquid inlet and laterally displaced therefrom; valve means in said central chamber including a valve for closing said liquid inlet when liquid is not being discharged, and a valve for closing said air inlet when liquid is being discharged; and means including a lever pivoted intermediate its ends for interconnecting said valves to cause either to close when the other is opened.
7. A vacuum-breaking device for a liquid discharge line descending to a receptacle open to atmosphere, comprising a casing adapted for connection into said line and provided with a descending passageway constituting, when installed, a portion of said line; said passageway including a

liquid inlet at the top, a liquid outlet at the bottom, and a central chamber connecting said inlet with said outlet, there being an air inlet into the central chamber located above the liquid inlet and laterally displaced therefrom; valve means in said central chamber including a valve for closing said liquid inlet when liquid is not being discharged, and a valve for closing said air inlet when liquid is being discharged; and lever means interconnecting said valves to cause either to close when the other is opened, means being included in the structure for causing the air valve to stand in open position and the liquid valve to stand in closed position whenever no liquid is being discharged.

8. A vacuum-breaking device for a liquid-discharge line descending to a receptacle open to atmosphere, comprising a casing adapted for connection into said line and provided with a descending passageway constituting, when installed, a portion of said line; said passageway including a liquid inlet at the top, a liquid outlet at the bottom and a central chamber connecting said inlet with said outlet, there being an air inlet into the central chamber located above the liquid inlet and laterally displaced therefrom; valve means in said central chamber including a valve for closing said liquid inlet when liquid is not being discharged, and a valve for closing said air inlet when liquid is being discharged; means including a lever pivoted intermediate its ends for interconnecting said valves to cause either to close when the other is opened; and weight means associated with said air valve and the related end of said lever for overbalancing the other end of said lever and the liquid-inlet valve to enable the air valve to fall by gravity to open position and to raise the liquid valve against gravity to closed position when no liquid is being discharged.

9. A vacuum-breaking device for a liquid-discharge line descending to a receptacle open to atmosphere, comprising a casing adapted for connection into said line and provided with a vertical passageway constituting, when installed, a portion of said line; said passageway including a liquid inlet at the top, a liquid outlet at the bottom vertically aligned with said inlet, and an enlarged central chamber connecting said inlet with said outlet, there being an air inlet into the central chamber laterally displaced from the liquid inlet; valve means in said enlarged central cham-

ber including a valve for closing said liquid inlet when liquid is not being discharged; and a valve for closing said air inlet when liquid is being discharged; lever means interconnecting said valves to cause either to close when the other is opened; and weight means associated with said air valve for overbalancing the weight of the liquid-inlet valve to enable the air valve to fall by gravity to open position and raise the liquid valve to closed position when no liquid is being discharged, said lever interconnection being such that the air valve is closed responsive to a small angular movement of said lever when discharging liquid strikes the water-inlet valve and forces it open, said central chamber being enlarged entirely around the liquid-inlet valve to enable an unrestricted discharge to occur when the control lever is given only a short angular movement, while the liquid-inlet valve remains interposed in the direct line of liquid discharge through the device to receive the impact of the discharge stream and maintain the air valve tightly closed independent of super-atmospheric pressure within the chamber.

10. A vacuum-breaking device for a liquid-discharge line descending to a receptacle open to atmosphere, comprising a casing adapted for connection into said line and provided with a descending passageway constituting, when installed, a portion of said line; said passageway including a liquid inlet at the top, a liquid outlet and an enlarged central chamber connecting said inlet with said outlet, there being an air inlet into the central chamber laterally displaced from the liquid inlet; valve means in said enlarged central chamber including a valve for closing said liquid inlet when liquid is not being discharged, and a valve for closing said air inlet when liquid is being discharged; means including a lever pivoted intermediate its ends for interconnecting said valves to cause either to close when the other is opened; and leak means associated with said liquid-inlet valve for insuring that a sub-atmospheric pressure in the liquid-discharge line above the liquid-inlet valve results in air, admitted through the open air-inlet valve, by-passing the closed liquid-inlet valve to cushion the surge back when super-atmospheric pressure is resumed.
